CLAIM

The ornamental design for a sleeve for electronic device, as shown and described.

DESCRIPTION

FIG. 1 is a perspective view including the front, top, and side of an embodiment of a sleeve for electronic device;
FIG. 2 is a perspective view including the rear, top, and side of the sleeve for electronic device of FIG. 1;

FIG. 3 is a front elevation view of the sleeve for electronic device of FIG. 1;

FIG. 4 is a rear elevation view of the sleeve for electronic device of FIG. 1;

FIG. 5 is a side elevation of the sleeve for electronic device of FIG. 1;

FIG. 6 is an opposite side elevation view of the sleeve for electronic device of FIG. 1;

FIG. 7 is a top plan view of the sleeve for electronic device of FIG. 1;

FIG. 8 is a bottom plan view of the sleeve for electronic device of FIG. 1;

FIG. 9 is a perspective view including the front, top, and side of an embodiment of a sleeve for electronic device;
FIG. 10 is a perspective view including the rear, top, and side of the sleeve for electronic device of FIG. 9;

FIG. 11 is a front elevation view of the sleeve for electronic device of FIG. 9;

FIG. 12 is a rear elevation view of the sleeve for electronic device of FIG. 9;

FIG. 13 is a side elevation of the sleeve for electronic device of FIG. 9;

FIG. 14 is an opposite side elevation view of the sleeve for electronic device of FIG. 9;

FIG. 15 is a top plan view of the sleeve for electronic device of FIG. 9;

FIG. 16 is a bottom plan view of the sleeve for electronic device of FIG. 9;

FIG. 17 is a perspective view including the front, top, and side of an embodiment of a sleeve for electronic device;

FIG. 18 is a perspective view including the rear, top, and side of the sleeve for electronic device of FIG. 17;

FIG. 19 is a front elevation view of the sleeve for electronic device of FIG. 17;

FIG. 20 is a rear elevation view of the sleeve for electronic device of FIG. 17;

FIG. 21 is a side elevation of the sleeve for electronic device of FIG. 17;

FIG. 22 is an opposite side elevation view of the sleeve for electronic device of FIG. 17;

FIG. 23 is a top plan view of the sleeve for electronic device of FIG. 17;

FIG. 24 is a bottom plan view of the sleeve for electronic device of FIG. 17;

FIG. 25 is a perspective view including the front, top, and side of an embodiment of a sleeve for electronic device;

FIG. 26 is a perspective view including the rear, top, and side of the sleeve for electronic device of FIG. 25;

FIG. 27 is a front elevation view of the sleeve for electronic device of FIG. 25;

FIG. 28 is a rear elevation view of the sleeve for electronic device of FIG. 25;

FIG. 29 is a side elevation of the sleeve for electronic device of FIG. 25;

FIG. 30 is an opposite side elevation view of the sleeve for electronic device of FIG. 25;

FIG. 31 is a top plan view of the sleeve for electronic device of FIG. 25;

FIG. 32 is a bottom plan view of the sleeve for electronic device of FIG. 25;

FIG. 33 is a perspective view including the front, top, and side of an embodiment of a sleeve for electronic device;

FIG. 34 is a perspective view including the rear, top, and side of the sleeve for electronic device of FIG. 33;

FIG. 35 is a front elevation view of the sleeve for electronic device of FIG. 33;

FIG. 36 is a rear elevation view of the sleeve for electronic device of FIG. 33;

FIG. 37 is a side elevation of the sleeve for electronic device of FIG. 33;

FIG. 38 is an opposite side elevation view of the sleeve for electronic device of FIG. 33;

FIG. 39 is a top plan view of the sleeve for electronic device of FIG. 33;

FIG. 40 is a bottom plan view of the sleeve for electronic device of FIG. 33;

FIG. 41 is a perspective view including the front, top, and side of an embodiment of a sleeve for electronic device;

FIG. 42 is a perspective view including the rear, top, and side of the sleeve for electronic device of FIG. 41;

FIG. 43 is a front elevation view of the sleeve for electronic device of FIG. 41;

FIG. 44 is a rear elevation view of the sleeve for electronic device of FIG. 41;

FIG. 45 is a side elevation of the sleeve for electronic device of FIG. 41;

FIG. 46 is an opposite side elevation view of the sleeve for electronic device of FIG. 41;

FIG. 47 is a top plan view of the sleeve for electronic device of FIG. 41;

FIG. 48 is a bottom plan view of the sleeve for electronic device of FIG. 41;

FIG. 49 is a perspective view including the front, top, and side of an embodiment of a sleeve for electronic device;

FIG. 50 is a perspective view including the rear, top, and side of the sleeve for electronic device of FIG. 49;

FIG. 51 is a front elevation view of the sleeve for electronic device of FIG. 49;

FIG. 52 is a rear elevation view of the sleeve for electronic device of FIG. 49;
